CONVERSION OF HYDROCARBONS

James P. Daugherty, Jr., Woodbury, N. J., assignor to Houdry Process Corporation, Dover, Del., a corporation of Delaware

Application February 10, 1933, Serial No. 656,064

6 Claims. (Cl. 196—52)

This invention relates to the production of lower boiling hydrocarbons such as benzine, gasoline, naphtha, kerosene and the like from high boiling distillates such as result from the distillation of crude petroleum and oils made by the destructive distillation of carbonaceous material.

Pyrolytic "cracking" or transforming of hydrocarbons is well known and various systems differing from one another only in minor details are in common use. A more recent development involves the catalytic conversion of hydrocarbons by a continuous process utilizing two or more converters containing catalytic material which is regenerated or reactivated in situ so that each converter may be alternately on stream and in regeneration, as indicated, for example in the copending application of Eugene J. Houdry, Serial No. 610,567, filed May 11, 1932. In the pyrolytic systems, it is common practice to effect continuous recycling of the residues from the fractionating column under the same temperature and pressure conditions, while in the aforementioned catalytic process the residues are segregated to provide separate and distinct passes at atmospheric or low pressures and at increasing temperatures in the later passes. The pyrolytic systems produce usually, from a fresh feed, a gasoline of rather low octane rating, as compared with the catalytic process, but appear to handle the more refractory residues with reasonable facility. On the other hand, the catalytic process makes its best yield in the early passes and produces a product which is more easily refined and stabilized than that resulting from the pyrolytic systems.

One object of the invention is to combine the pyrolytic and catalytic processes in such a way as to secure certain advantages of both while avoiding certain of their disadvantages. Other objects will be apparent from the detailed description which follows.

One concrete embodiment of the invention is illustrated diagrammatically in the single figure of the accompanying drawing.

The apparatus as disclosed combines a catalytic system, indicated generally by reference character A, with a pyrolytic system, indicated by B, to produce a high yield of low boiling hydrocarbons, such as gasoline, having a good anti-knock rating. The catalytic system conforms in general to that disclosed in the aforesaid copending Houdry application, Serial No. 610,567. It comprises a tubular heater 1a and two or more catalytic converters 2a containing catalytic ma-

terial capable of making the desired conversion, such as a contact mass consisting of an activated hydrosilicate of aluminum with or without the addition of active metal oxides preferably in molded form, as disclosed, for example, in the copending application of Eugene J. Houdry, Serial No. 600,581, filed March 23, 1932, so as to be capable of regeneration in situ. The catalytic converters are arranged for alternate operation on stream and in regeneration, the vaporized products from heater 1a being fed thereto through valved line 3a at atmospheric pressure or low superatmospheric pressure and at a temperature of from 750° to 1000° F., while the converted products are discharged through valved line 4a. The regenerating medium, which may be an oxidizing agent, such as air diluted, if desired, with steam or flue gas, may be admitted through a valved connection 5a and the fumes carried away by connection 6a.

The pyrolytic system may be of any known or suitable type, either liquid or vapor phase, such as Dubbs, Cross, tube and tank, the Florez, etc., the one indicated comprising a tubular heater 1b and a reaction or evaporating chamber 2b. The hydrocarbon vapors from heater 1b are fed to chamber 2b by a line 3b, under substantial pressure and at a temperature ranging from 850° to 1100° F., and the converted products are discharged through a line 4b. Tarry residues may be drawn from the bottom of reaction chamber 2b through a valved line 5b.

Each system has its own fractionating column, line 4a from catalytic system A discharging into fractionator 7a, while line 4b from pyrolytic system B discharges into fractionator 7b. Trimming coils 8a and 8b may be provided in the tops of each of the fractionating columns, if desired, to control the temperatures thereof. The vapors issue from the fractionators through lines 9a and 9b, respectively, to be condensed, refined and stabilized, either separately or together, as may be desired, by other apparatus which is not disclosed since it forms no part of the present invention.

The fresh feed, such as a gas oil, is fed by line 10 direct or optionally through a heating coil 11 in the top of fractionator 7a, to heat exchangers 12a and 12b in vapor lines 4a and 4b, respectively, leading from the two converting systems, and is discharged in a preheated condition into an accumulator tank 13. A line 14 is provided for pumping material from the bottom of the accumulator tank as feed for heater 1a of the catalytic system, while feed for heater 1b of

the pyrolytic system is recycle stock which is pumped through line 15 from the bottom of fractionator 1b. A connection 16 from the bottom of fractionator 1a permits recycle stock from the bottom of the latter to be pumped optionally or in any desired proportion through a valved branch 17 either into accumulator tank 13, or by valved branch 18 into fractionator 1b. Tank 13 may be vented to either of the fractionating columns, as desired. The line 19 indicates such a connection to fractionator 1a.

By a proper proportioning of the two systems, and by pumping the bulk of the recycle stock from fractionator 1a to fractionator 1b, the 15 position of the material fed from tank 13 to heater 1a of the catalytic system may be kept close to fresh feed or gas oil, so as to secure the high yield and high octane characteristics of the early 20 passes in the catalytic process, while the recycling stock is handled, to a large extent, if not exclusively, by the pyrolytic system. In this way, existing pyrolytic plants may be combined with continuously operating catalytic plants which 25 supply to them a cracking stock from which they can produce a gasoline of high octane number. The products from both systems may be treated individually or blended to facilitate the stabilizing of the same.

I claim as my invention:

- 30 1. In apparatus for the conversion of higher boiling hydrocarbons into lower boiling hydrocarbons, in combination, a catalytic system comprising means for heating hydrocarbons in a stream and at least two converters connected thereto for operation alternately on stream and in regeneration and containing catalytic material capable of making the desired conversion and of regeneration in situ, a pyrolytic system comprising means for heating hydrocarbons and a chamber connected thereto, a fractionating column connected to said catalytic system to receive the products therefrom, a second fractionating column connected to said pyrolytic system to receive the products therefrom, means for 35 passing fresh feed into heat exchange with the products of both said systems and thence to said heating means of said catalytic system, means for sending the bottoms from said second fractionating column to said heating means of said pyrolytic system, and means including connections and controls for selectively mingling bottoms from said first fractionating column with said fresh feed and with the contents of said second fractionating column.
- 40 2. In apparatus for the conversion of higher boiling hydrocarbons into lower boiling hydrocarbons, in combination, a catalytic system comprising means for heating hydrocarbons in a stream and at least two converters connected thereto for operation alternately on stream and in regeneration and containing catalytic material capable of making the desired conversion and of regeneration in situ, a pyrolytic system comprising means for heating hydrocarbons and a chamber connected thereto, a fractionating column connected to said catalytic system to receive the products thereof, a second fractionating column connected to said pyrolytic system to receive the products thereof, means for directing 45 fresh feed to the heating means of said catalytic system, means to add bottoms from said first fractionating column to said fresh feed, means to discharge bottoms from said first fractionating column into said second fractionating column, and means for conducting bottoms from

said second fractionator to the heating means of said pyrolytic system.

3. In apparatus for the conversion of higher boiling hydrocarbons into lower boiling hydrocarbons, in combination, a catalytic system comprising means for heating hydrocarbons in a stream and at least two converters connected thereto for operation alternately on stream and in regeneration and containing catalytic material capable of making the desired conversion and of regeneration in situ, a pyrolytic system comprising means for heating hydrocarbons and a chamber connected thereto, a fractionating column connected to said catalytic system to receive the products thereof, a second fractionating column connected to said pyrolytic system to receive the products thereof, an accumulator tank, heat exchangers in the connections to both said fractionators, means sending fresh feed through said exchangers and thence into said tank, means for discharging recycle stock from the bottom of said first fractionator at will and in any desired proportion into said tank and into said second fractionator, a connection from said tank to the heating means of said catalytic system, and a connection from the bottom of said second fractionator to the heating means of said pyrolytic system.

4. In apparatus for the conversion of higher boiling hydrocarbons into lower boiling hydrocarbons, in combination, a catalytic system comprising means for heating hydrocarbons in a stream and at least two converters connected thereto for operation alternately on stream and in regeneration and containing catalytic material capable of making the desired conversion and of regeneration in situ, a pyrolytic system comprising means for heating hydrocarbons and a chamber connected thereto, a fractionating column connected to said catalytic system, a second fractionating column connected to said pyrolytic system, an accumulator tank into which preheated fresh feed is discharged, valved connections from the bottom of said first fractionator to said tank and to said second fractionator, a vent connection from said tank, a feed connection from said tank to the heating means of said catalytic system, and a feed connection from the bottom of said second fractionator to the heating means of said pyrolytic system.

5. In apparatus for the conversion of higher boiling hydrocarbons into lower boiling hydrocarbons, in combination, a catalytic system comprising means for heating hydrocarbons in a stream and at least two converters connected thereto for operation alternately on stream and in regeneration and containing catalytic material capable of making the desired conversion and of regeneration in situ, a pyrolytic system comprising means for heating hydrocarbons and a chamber connected thereto, a fractionating column connected to said catalytic system, a second fractionating column connected to said pyrolytic system, an accumulator tank into which preheated fresh feed is discharged, means for discharging bottoms from said first fractionator at will either into said tank or into said second fractionator, means for feeding material from said tank to the heating means of said catalytic system, means for feeding material from the bottom of said second fractionator to the heating means of said pyrolytic system, and a vent connection from said tank into said first fractionator.

6. Process of converting higher boiling hydrocarbons into lower boiling hydrocarbons which

- comprises passing the starting material through a vaporizing zone and then at low pressure into a converting zone containing catalytic material having selective adsorptive properties maintained in the temperature range of 750° to 1000° F., discharging the vapors into a vapor fractionating zone where partial condensation occurs, withdrawing the heavy condensate from the bottom of the fractionating zone, mixing a part of the heavy condensate with preheated fresh feed to form the starting material for said vaporizing zone and then passing the mixture to said vaporizing zone, introducing the remainder of the heavy condensate into the lower portion of a second vapor fractionating zone, withdrawing heavy condensate from the bottom of said second fractionating zone, sending said last named condensate through a cracking zone and then at relatively high pressure into a pyrolytic reaction zone maintained in the temperature range of 850° to 1100° F., discharging the vapors from said last named reaction zone into said second fractionating zone, and withdrawing the overhead vapors from both said fractionating zones to provide the desired lower boiling hydrocarbons. 5 10

JAMES P. DAUGHERTY, JR.
